UNITED STATES PATENT OFFICE

171,314

GAS FIRED SPACE HEATER

Eugene G. Siegler and Raymond J. Siegler,
Marion County, Ill.

Application March 19, 1953, Serial No. 24,101

Term of patent 14 years

(Cl. D81—10)

To all whom it may concern:

Be it known that we, Eugene G. Siegler and Raymond J. Siegler, citizens of the United States, and residents of the county of Marion and State of Illinois, have invented a new, original, and ornamental Design for a Gas Fired Space Heater, of which the following is a specification, reference being had to the accompanying drawing forming part thereof.

Fig. 1 is a perspective view showing the front, top, and one side of a gas fired space heater embodying our new design;

Fig. 2 is a perspective view thereof showing the rear, top, and opposite side; and

Fig. 3 is an elevational view showing the right side in Fig. 1.

We claim:

The ornamental design for a gas fired space heater, substantially as shown.

EUGENE G. SIEGLER.

RAYMOND J. SIEGLER.
